UNITED STATES PATENT OFFICE.

JOHN CLEAVE, OF CREDITON, ENGLAND.

CANDY-KETTLE.

SPECIFICATION forming part of Letters Patent No. 601,747, dated April 5, 1898.

Application filed March 3, 1897. Serial No. 625,808. (No model.) Patented in England October 5, 1896, No. 22,018.

To all whom it may concern:

Be it known that I, JOHN CLEAVE, a subject of the Queen of Great Britain, residing at Crediton, in the county of Devon, Kingdom of England, have invented certain new and useful Improvements in Kettles, (for which I have received Letters Patent in Great Britain, No. 22,018, bearing date October 5, 1896,) of which the following is a full and complete specification, such as will enable those skilled in the art to which it appertains to make and use the same.

This invention relates to improvements in kettles for boiling sugar and other articles which are heated by means of steam; and the object thereof is to provide an improved device of this class which is simple in construction and operation and comparatively inexpensive and which may be used wherever such devices of this class are required.

The invention is fully disclosed in the following specification, of which the accompanying drawings form a part, in which—

Figure 1 is a central vertical section of my improved kettle and showing the method of constructing and operating the same, together with the frame by which it is supported; and Fig. 2, an opposite side view thereof, part of the construction being shown in section.

In the drawings forming part of this specification the separate parts of my improvement are designated by the same numerals of reference in each of the views, and in the practice of my invention I provide a suitable frame, which consists of end portions 5, which are preferably composed of metal and which are supported by legs 6, and the end portions of the frame or support are preferably circular in form, and at the top thereof are cross-heads 7, to which are secured blocks 8, in which are mounted journals or shafts 9, the cross-heads 7 and the blocks 8 serving simply to form bearings for said journals or shafts.

The journals or shafts 9 are free to turn in their bearings, and one of said journals or bearings is provided with a lever 10, by which the kettle may be turned or agitated, and in the construction of my improved kettle I form the body portion 11 thereof of copper or any preferred material, and I secure around the top thereof heavy metal bands 12, and around the entire body portion of the bottom

of the kettle I coil a copper pipe 13, and centrally of the bottom of the kettle one end of said pipe is bent downwardly, as shown at 55 14, and is provided with a discharge-valve 15, of any preferred form of construction, said valve being preferably so formed as to serve as an escape for the exhaust-steam and the water of condensation and to allow only a 60 certain amount or a predetermined amount of said exhaust-steam and the water of condensation to escape, and said valve may be closed only when desired. The other end of the pipe from which the coil 13 is formed projects outwardly, as shown at 16, and is connected at 17 by a ball-and-socket joint with a steam-supply pipe 18, and the pipe 16 is free to turn in the coupling at 17.

The coil 13 is held in place by metal bands 70 19, which pass transversely around the bottom of the kettle and around said coil in opposite directions, as shown in Figs. 1 and 2, and the ends of which are secured to the ring or band 12 around the top of the kettle. I 75 also inclose the kettle by a thin metal casing 20, which is also secured to said ring or band 12 and between which and the coil 13 is a narrow space 21, and the metal casing 20 is preferably perforated, and around the casing 20 80 and also secured to the ring or band 12 is another casing 22 of galvanized sheet metal or any preferred material, and the space between the casings 21 and 22 is filled with asbestos, as shown at 23, or with any other suitable or 85 similar material which is adapted to serve as a non-conductor of heat.

The downwardly-directed extension 14 of the coil 13 passes through a tube 24, which extends between the casings 20 and 22, and 90 the kettle is provided with a detachable cover 25, having handles 26 and provided with a downwardly-directed flange or rim 27, which fits within the top of the kettle, and said cover is provided with a central opening 28, which 95 is preferably of the form shown in Fig. 1, and at one side of the kettle is secured a handle 29 and at the opposite side a lug or projection 30, which is also adapted to serve as a handle, and, as will be apparent, the material within 100 the casing may be shaken or agitated at any time by means of the lever 10, and said lever is also adapted to serve as means for tipping the kettle or turning the same so as to dis-

charge the contents thereof, and in this operation of shaking or agitating the contents of the kettle and of turning the same so as to discharge the contents thereof the extension 5 16 of the coil 13 will turn in the coupling at 17 without interfering with the passage of the steam into and through the coil 13.

My improvement is simple in construction and operation and is perfectly adapted to accomplish the result for which it is intended, and it will be apparent that changes in and modifications of the construction herein described may be made without departing from the spirit of my invention or sacrificing its 15 advantages.

Having fully described my invention, I claim as new and desire to secure by Letters Patent—

20 The herein-described kettle comprising a pivotally-mounted kettle, a continuous coil

of pipe surrounding the same and being in contact therewith, a steam-pipe communicating with said coil through a universal joint, a discharge-spout connected with the lower end of said coil, a casing inclosing the said 25 coil, a double casing inclosing the first-named casing, the inner wall of which is held at a predetermined distance therefrom, a packing of asbestos between the walls of said double casing, and means for revolving said kettle, 30 substantially as and for the purpose described.

In testimony that I claim the foregoing as my invention I have signed my name, in presence of the subscribing witnesses, this 15th day of February, 1897.

JOHN CLEAVE.
